TEMPERATURE CONTROL

Ralph M. Heintz, Palo Alto, Calif., assignor to
 Heintz & Kaufman, Ltd., San Francisco, Calif.,
 a corporation of Nevada

Application December 9, 1932, Serial No. 646,403

6 Claims. (Cl. 62—7)

My invention relates to a temperature control, and more particularly to a device which utilizes the temperature regulation provided by the melting or solidification of a crystalline substance.

5 Among the objects of my invention are: To provide a constant temperature bath; to provide a device for maintaining an object at a constant temperature; to provide a device for maintaining an oscillating crystal at a constant temperature; and to provide a simple device operative to break an electrical circuit upon congelation of a crystalline substance.

10 Other objects of my invention will be apparent or will be specifically pointed out in the description forming a part of this specification, but I do not limit myself to the embodiment of my invention herein described, as various forms may be adopted within the scope of the claims.

Referring to the drawing:

20 Figure 1 is a longitudinal view, partly in section and partly in elevation of a temperature control bath.

Figure 2 is a face view in elevation of a circuit breaker operative on congelation of the liquid in the bath, taken from a plane indicated by the line 2—2 in Figure 1.

30 While there are many objects which it is desirable to maintain at a constant temperature, I have shown my invention as applied to a quartz crystal. It is customary in vacuum tube oscillator radio transmitting stations to use such a crystal to control the frequency of the oscillator, and in order to maintain the frequency constant, the crystal must be kept at a constant temperature.

35 I have provided a device in which such a crystal, or other objects as desired, may be kept and maintained at a uniform and unvarying temperature.

40 Broadly speaking my invention comprises a container filled with a crystalline substance, liquid at room temperature. I provide means for maintaining this liquid in a partially congealed or frozen state, and place my object to be maintained at a constant temperature in the unfrozen portion. Inasmuch as the congelation or melting is never allowed to be completed the temperature 45 will not vary, as when a crystalline substance undergoes either melting or solidifying, its temperature remains constant from the instant that melting or solidifying begins, until the process is completed.

45 In the drawing, which represents a preferred embodiment of my invention, employing water as the crystalline substance, a double-walled container 1 is mounted on a base 2, and filled with 50 a quantity of water 3, preferably distilled.

A brine coil 4 is placed in the inter-wall space, close to the inside of the container, and the remainder of the space is filled with a good heat insulator 5 such as ground cork, asbestos wool, or the like.

55 The brine coil is connected to a refrigerating system, so designated on the drawing, by means of pipe fittings 6—6. This refrigerating system is electrically operated and has, emerging from it, energizing supply wires 7 and 8.

A quartz crystal 9, together with its contact electrodes 10 and 11, is enclosed in a control box 12 held in the center of the container by conduits 13 and 14 through which run crystal leads 15 and 16 by means of which the crystal may be 60 connected in a vacuum tube or other circuit. All precautions are taken to prevent any liquid from entering the control box.

65 Mounted on the upper rim of the container is a circuit-breaker mechanism comprising a motor 75 17 having motor leads 18 emerging therefrom, which may be directly connected to alternating current mains 19. This motor, preferably of low power, may be designed to run at a slow speed, or may be geared down to a drive-shaft 20 which 70 carries on its outer end a breaker disc 21, of insulating material such as bakelite or lava.

75 The breaker disc has a central stud 22 to which is loosely fitted a contact arm 23 long enough to enter the water to a substantial depth 80 when rotated, and provided with a drip-cup 24, and an arm contact 25.

85 A contact bracket 26 is fixed to the disc, extending parallel to the arm, provided with a bracket contact 27, and is connected to a metal 90 rim 28 by a link 29. The arm contact and the bracket contact are directly opposed, and are held together firmly by a spring 30, attached at one end to a short arm stub 31 extending away from the main portion of the arm on the other 95 side of the central stud 22, and to a spring stud 32 attached to the disc 21. The two contact points thus make electrical connection between the rim 28 and the arm.

100 I prefer to make the central stud 22 the end of the drive-shaft 20, and make the drive-shaft of metal, so that I may utilize the motor frame as a means of making connection to the arm.

105 The extreme end of the contact bracket 26 is provided with an insulating stop-bar 33, passing through a boss 34 in the arm and carrying a stop 35 at its end. This stop prevents the contacts from opening too far and acts to stall the motor, as will be described later.

110 Electrical connection is made to the rim 28 by 110

a brush 36 held by a connection post 37. This post is mounted on a brush bracket 38 fixed to the top of the motor.

I am now able to connect one of the energizing wires 7 to the mains 19, and connect the other wire 8 directly to the motor 17. Connection is then made through the drive-shaft 20, arm 23, contacts 25 and 27, bracket 26, link 29, rim 28, brush 36 and post 37 back to the mains 10 through wire 39.

When the mains are energized, the refrigeration system will start up, as the contacts 25 and 27 are closed, and the motor 17 will start rotating. I prefer to rotate the arm 23 about once per 15 second and the motor mechanism 17 may well be that of the well known synchronous clock. It is however perfectly feasible to operate the entire device from D. C. mains, using proper motors, as the exact time of arm rotation is immaterial.

Inasmuch as the water offers no resistance to the arm as it rotates, the contacts will remain closed. Freezing of the water will start when the temperature of the entire amount of water 25 reaches 32°, and the freezing, or congelation will take place progressively out from the walls of the container as indicated by the dotted line 40.

When the frozen crystals reach the point where the arm is rotating, which takes place before the 30 congelation reaches the control box, the arm will be blocked by ice and will cease rotating. The disc, however, will keep on rotating, against the spring 32, open the contacts 25 and 27, until it also is stopped by the stop 35 hitting the boss 34. The motor 17 then stalls, and will remain stalled until the ice crystals melt. In the meantime, the opening of the contacts has stopped operation of the refrigerator, and the ice formed will start to melt. When it melts from around 40 the arm, the arm will start rotating again and the contacts will close. This cycle is repeated to the end that there will always be a layer of ice around the inside of the container, with unfrozen liquid in the center. The temperature will thus 45 be kept accurately at 32°, and objects placed in the control box will also be maintained uniformly at that temperature.

I claim:

1. A constant temperature bath comprising a 50 container for receiving a fluid, means for freezing a portion of said fluid, means for preventing the remaining portion from freezing, and a receptacle for an article to be kept at a constant temperature positioned to be surrounded by said unfrozen portion.

2. A constant temperature bath comprising a

container for receiving a fluid, means for freezing a portion of said fluid, means for preventing the remaining portion from freezing, and a receptacle for a quartz crystal positioned to be surrounded by said unfrozen portion.

80

3. A constant temperature bath comprising a container having walls, refrigerating coils in said walls, fluid in said container, electrically-driven refrigerating means abstracting heat from said coils to freeze said liquid, means for supplying current to said refrigerating means, means operating to break said supply current to said refrigerating means when a portion of said liquid is frozen, and a receptacle for a temperature effected portion of an oscillatory-electrical system positioned to be surrounded by the unfrozen portion of said liquid.

85

4. A constant temperature bath comprising a container having walls, refrigerating coils in said walls, fluid in said container, electrically-driven refrigerating means abstracting heat from said coils to freeze said liquid, means for supplying current to said refrigerating means, means operating to break said supply current to said refrigerating means when a portion of said liquid is frozen, means for closing said circuit when the frozen portion starts to melt, and a receptacle for a temperature effected portion of an oscillatory-electrical system positioned to be surrounded by the unfrozen portion of said liquid.

90

5. A constant temperature bath comprising a container having walls, refrigerating coils in said walls, fluid in said container, electrically-driven refrigerating means abstracting heat from said coils to freeze said liquid, means for supplying current to said refrigerating means, means operating to break said supply current to said refrigerating means when a portion of said liquid is frozen, means for closing said circuit when the frozen portion starts to melt, and a receptacle for a temperature effected portion of an oscillatory-electrical system positioned to be surrounded by the unfrozen portion of said liquid.

95

6. A constant temperature bath comprising a container having walls, refrigerating coils in said walls, fluid in said container, electrically-driven refrigerating means abstracting heat from said coils to freeze said liquid, means for supplying current to said refrigerating means, and an arm movable through said liquid, said arm carrying contacts adapted to be broken when said arm is stopped by congelation of said liquid, said refrigerating means being controlled by current passing through said contacts.

105

7. A constant temperature bath comprising a container having walls, refrigerating coils in said walls, fluid in said container, electrically-driven refrigerating means abstracting heat from said coils to freeze said liquid, means for supplying current to said refrigerating means, an arm movable through said liquid, said arm carrying contacts adapted to be broken when said arm is stopped by congelation of said liquid, said refrigerating means being controlled by current passing through said contacts.

110

8. A constant temperature bath comprising a container having walls, refrigerating coils in said walls, fluid in said container, electrically-driven refrigerating means abstracting heat from said coils to freeze said liquid, means for supplying current to said refrigerating means, an arm movable through said liquid, said arm carrying contacts adapted to be broken when said arm is stopped by congelation of said liquid, said refrigerating means being controlled by current passing through said contacts, and means for closing said contacts when said arm is freed by the melting of said congealed liquid.
